(57) **CLAIM**

The ornamental design for a mirror, as shown and described.

DESCRIPTION

FIG. 1 is a perspective view of a mirror showing my new design where the mirror is in a first configuration of use; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of the mirror where the mirror is in a second configuration of use; FIG. 10 is a perspective view of the mirror where the mirror is in a third configuration of use; FIG. 11 is an exploded perspective view of the mirror; and, FIG. 12 is an enlarged view of portion 12 shown in FIG. 1. The broken lines in the drawings depict portions of the mirror that form no part of the claimed design.
